US0D1006764S

(12) **United States Design Patent** (10) **Patent No.:** **US D1,006,764 S**
(45) **Date of Patent:** **** Dec. 5, 2023**

(54) **BOW CABLE MANAGEMENT SYSTEM**

(71) Applicant: **Robert Stephan**, Mesa, AZ (US)

(72) Inventor: **Robert Stephan**, Mesa, AZ (US)

(**) Term: **15 Years**

(21) Appl. No.: **29/839,320**

(22) Filed: **May 19, 2022**

(51) LOC (14) Cl. **13-03**

(52) U.S. Cl.

USPC **D13/155**; D22/109

(58) **Field of Classification Search**

USPC D13/156, 155, 157; D8/394, 356;
D22/109

CPC H02G 3/14; H02G 7/12; H02G 3/0418;
F41G 1/467

See application file for complete search history.

(57) **CLAIM**

The ornamental design for the bow cable management system, as shown and described.

DESCRIPTION

FIG. 1 is a first top perspective view of a bow cable management system showing my new design;

FIG. 2 is a second top perspective view of the bow cable management system;

FIG. 3 is a third top perspective view of the bow cable management system;

FIG. 4 is a fourth top perspective view of the bow cable management system;

FIG. 5 is a left side view of the bow cable management system;

FIG. 6 is a right side view of the bow cable management system;

FIG. 7 is a front elevational view of the bow cable management system;

FIG. 8 is a rear elevational view of the bow cable management system;

FIG. 9 is a top plan view of the bow cable management system;

FIG. 10 is a bottom plan view of the bow cable management system;

FIG. 11 is a first bottom perspective view of the bow cable management system; and,

FIG. 12 is a second bottom perspective view of the bow cable management system.

The broken lines shown represent portions of the bow cable management system that form no part of the claimed design.

1 Claim, 12 Drawing Sheets
